LAMP

Frank M. Spezzano, Bristol, Pa.

Application August 5, 1948, Serial No. 147,960

Term of patent 14 years

(Cl. D48—20)

To all whom it may concern:

Be it known that I, Frank M. Spezzano, a citizen of the United States, residing at Bristol, county of Bucks, and State of Pennsylvania, have invented a new, original, and ornamental Design for a Lamp, of which the following is a specification, reference being had to the accompanying drawings, forming a part thereof, wherein:

I claim:

The ornamental design for a lamp, as shown.

FRANK M. SPEZZANO.
